W. A. STEWART.

CONDIMENT HOLDER.

APPLICATION FILED SEPT. 26, 1917.

1,269,127.

Patented June 11, 1918.

Inventor

W. A. STEWART

By *Watson E. Coleman*

Attorney

UNITED STATES PATENT OFFICE.

WILLIAM A. STEWART, OF SAN FRANCISCO, CALIFORNIA.

CONDIMENT-HOLDER.

1,269,127.

Specification of Letters Patent. Patented June 11, 1918.

Application filed September 26, 1917. Serial No. 193,308.

To all whom it may concern:

Be it known that I, WILLIAM A. STEWART, a subject of the King of England, residing at San Francisco, in the county of San Francisco and State of California, have invented certain new and useful Improvements in Condiment-Holders, of which the following is a specification, reference being had to the accompanying drawings.

10 This invention relates to condiment holders and has for its primary object to provide simple and effective means for loosening or breaking up salt or like condiments in a container, when the comminuted particles 15 become caked or packed from the effects of moisture or dampness.

It is also an important object of the invention to provide a device of the above character which is so constructed that the 20 salt may be scraped or removed from the under side of the perforated top or cap of the holder so as to open or clear the perforations therein.

It is another and more particular object 25 of the invention to provide a condiment holder constructed in a plurality of sections including a rotatable cap or perforated top section, a relatively stationary scraper of improved form secured to the section of the 30 holder next adjacent the rotary cap, and an agitator extending through the body of the holder and rotatably mounted on the base wall thereof, the upper end of the agitator being detachably connected to the rotary cap 35 for rotation thereby.

It is also a further general object of the invention to provide a device for the above purpose, which is simple in its construction, highly efficient in practical use, and convenient and serviceable for the purpose in view.

With the above and other objects in view, my invention consists in the novel features of construction, combination and arrangement of parts to be hereinafter more fully 45 described, claimed and illustrated in the accompanying drawing, in which,

Figure 1 is a side elevation illustrating one embodiment of my invention;

Fig. 2 is a longitudinal section taken on 50 the line 2-2 of Fig. 1;

Fig. 3 is a section taken on the line 3-3 of Fig. 2;

Fig. 4 is a detail perspective view illustrating a modified form of the rotatable 55 agitator; and

Figs. 5 and 6 are similar views illustrating still further modifications.

Referring in detail to the drawing, 5 designates the main body section of the condiment holder which preferably, though not necessarily, tapers to its upper end where the holder section is provided with exterior screw threads indicated at 6, and an annular bead 7 at the base of this threaded section. A relatively short body section 8 has interior threads on one end for engagement with the threads 6 and is also formed on said end with an outwardly projecting, annular bead 9. The section 8 of the holder has an outwardly projecting flange 10 formed upon its upper end and an annular bead 11 formed thereon below and adjacent to said flange. The rotatable cap 12 is provided upon its open end with an outwardly projecting, annular open bead 13 to receive the flange 10 75 on the holder section 8, whereby said cap is rotatably supported.

A rod 14 extends axially through the holder sections and the cap 12, and the lower end thereof is rotatably engaged in a suitable bearing seat 15 on the base wall of the body section 5. The upper end of this rod is square and seated in a socket 14^a centrally formed in the under side of the wall of the cap 12. This rod is provided with 80 alternately arranged, horizontal arms 16 projecting from relatively opposite sides thereof in the body section 5 of the holder. It will thus be understood that, by the rotation of the cap 12, the rod 14 will also be 85 rotated and the contents of the holder within the body 5 agitated and broken up by means of the arms 16.

A resilient wire 17 has its extremities fixed in any preferred manner to the section 8 of 95 the holder in spaced relation to the upper end thereof, as indicated at 18. Adjacent to each of the fixed ends of this wire, the same is spirally coiled, as at 19, though if desired, such coils may be omitted. The 100 wire extends upwardly from the coils 19 and has its intermediate portion curved or bowed and centrally flattened, as at 20. The spiral coils 19 act to resiliently force the intermediate portion 20 of the wire into 105 frictional bearing contact against the under side of the cap wall 12 which is perforated in the usual manner, as shown at 21. It will thus be seen that, in the rotation of the cap 12 to break up the condiment in the 110

body of the holder, the wire 17 will have a scraping action against the under side of the rotatable cap, thereby removing the salt which may have become caked thereon over 5 the perforations 21. Upon the inversion of the holder and the agitation of its contents, the latter will flow freely through the open perforations. It will, of course, be understood that the portion 20 of the wire 17 is 10 centrally formed with an opening through which the socket 14^a extends.

In Figs. 4, 5 and 6, I have illustrated several modified forms of the agitator which may be employed in connection with my invention. In Fig. 4, this agitator consists of the rods or flat bars 22 which are arranged upon opposite sides of the central rod 14' and have their lower ends connected to said central rod by a horizontal bar 23. These 20 rods 22 converge to their upper ends, where they are suitably fixed to the rod 14'. In Fig. 5, I have illustrated another form of the agitator consisting of a tapering, metal plate 24 suitably secured to the central rod 25 of the agitator. This plate is provided with a plurality of spaced openings 25 therein through which the condiment may freely pass in the rotation of said plate. In Fig. 6, the spaced rods 22' are connected to the 30 central agitator rod by a plurality of short, horizontal rods 26 alternately arranged upon opposite sides of the central rod of the agitator. It will also be manifest that many other forms of this agitating means might 35 be utilized. I have herein described a particular sectional construction of the holder, but it is obvious that if desired, the intermediate section 8 might be eliminated and the rotatable cap mounted upon the upper 40 end of the single body section 5.

I have above referred to a holder consisting of a main body section, a rotatable top or cap section, and an intermediate, relatively fixed section. It is to be understood, 45 however, that in practice, the sections may be multiplied as desired. For instance, an additional section may be interposed between the fixed section 8 and the cap section for independent rotation, and to this interposed section, the agitator may be connected.

From the foregoing description, taken in connection with the accompanying drawing, the construction, manner of operation 55 and several advantages of the device will be clearly and fully understood. It will be seen that I have produced a very simply constructed and inexpensive holder for condiments provided with means for positively 60 breaking up the material when it becomes caked or packed owing to moisture entering the holder. The device may be easily operated to entirely free the perforations in

the cap of the salt or other condiments so that there will be a free and unrestricted 65 flow of the latter. The several sections of the holder may be made of metal or any other desired material, and while I have herein pointed out the form, construction and arrangement of the several elements 70 employed, it is manifest that these detail features may be variously modified, and I, therefore, reserve the privilege of adopting all such legitimate changes as may be fairly embodied within the spirit and scope of the 75 invention as claimed.

Having thus fully described my invention, what I desire to claim and secure by Letters Patent is:—

1. A condiment holder including a fixed 80 section and a perforated, rotatable section, and a relatively fixed scraping element extending within the rotatable section and formed with a spring coil to yieldingly urge said element into effective scraping engagement with the wall of the rotatable holder section.

2. A condiment holder including a fixed section, a perforated cap section rotatably mounted upon said fixed section of the 90 holder, and a relatively fixed bowed scraping element extending within said cap section and provided with a spring coil yieldingly urging the medial portion of said element into scraping engagement with the 95 perforated wall of said cap section.

3. A condiment holder including a fixed section, a perforated cap section rotatably mounted upon the fixed section of the holder, and a length of resilient wire fixed 100 at its extremities to said fixed section, said wire adjacent each of its ends having a spring coil therein, the intermediate portion of the wire being curved and having frictional scraping engagement with the 105 under side of the cap wall.

4. A condiment holder including a body section, an intermediate section detachably connected to the body section, a perforated cap section rotatably mounted upon the intermediate section, and a length of resilient wire fixed at its extremities to the wall of the intermediate section and having a curved, intermediate portion extending within the cap section, said wire, adjacent each of its 115 ends, having a spiral coil formed therein whereby the intermediate portion of the wire is yieldingly urged into frictional scraping engagement with the wall of the cap section.

In testimony whereof I hereunto affix my signature in the presence of two witnesses.

WILLIAM A. STEWART.
